UNITED STATES PATENT OFFICE.

SAMUEL S. WEED, OF STONEHAM, MASSACHUSETTS.

MACHINE FOR MAKING PRINTERS' TYPES.

Specification forming part of Letters Patent No. 13,609, dated September 25, 1855.

To all whom it may concern:

Be it known that I, SAMUEL S. WEED, of Stoneham, in the county of Middlesex and State of Massachusetts, have invented a new and useful or Improved Machine for Making Printers' Types by Pressure; and I do hereby declare that the same is fully described and represented in the following specification and the accompanying drawings, letters, figures, and references thereof.

Of such drawings, Figure 1 denotes a top view of my said machine. Fig. 2 is a side elevation of it. Fig. 3 is a horizontal section of the movable and bed dies and feeding apparatus at or near one corner of the machine. Fig. 4 is an inner side view of the bed-die. Fig. 5 is an inner side view of the movable body-die.

The object of my machine is to manufacture copper or other metallic printing types from a rod or rods, such being separated by the mechanism into blanks or short pieces, and each of such blanks forged with a body and a letter of right shape. Common printing types are usually made by casting in a mold the metal of which they are composed, although what are termed "book-binders' stamping-types" are generally made of copper or brass, and are cut or formed by hand labor or workmen with proper tools. I am not aware that letter-press types for printing have been made from wire or rods and in dies by pressure. That such can be accomplished at about the cost of making founded type and so as to produce a type in copper or brass, not only equal in finish to such founded type, but far superior in point of durability, I have fully demonstrated by a machine substantially of the kind to be hereinafter specified.

My machine, although in many respects similar to machines for making rivets or nails by pressure in dies, is new in its application to the manufacture of types, and differs materially, to the best of my knowledge, from any such machines for making nails or such like articles.

In the drawings, (see Figs. 1, 2, and 3,) A denotes an open frame for sustaining the operative parts of the machine. In the middle of such frame is a vertical shaft, B, which carries a horizontal cam, C, formed, as seen in Fig. 1, to operate in connection with four pit-

men, D D D D, and four series of toggles or progressive levers, E E, F F, G G, H H, arranged about the cam and inside of the upper post of the frame A, seen as in Fig. 1. The toggles abut against and are jointed to bearers or blocks a a, b b, disposed at or near opposite corners of the frame, while at the two opposite corners are arranged the type-forming dies and mechanism for cutting off the rod. Each set of these dies is composed of a stationary body or bed die, I, a movable bed or body die, K, a letter-die, L, a bottoming-die, M, and receiving-orifice and separator N, the positions of the several parts with respect to each other being seen in the drawings.

The letter-die is for forming the letter on one end of the type. The body-dies form the body in the shape required. The bottoming-die squeezes or forms the opposite end of the type, and, with the letter-die, determines the length of its body. The receiving-orifice N has the rod extended through it from the feeding mechanism, and during its movement it carries said rod against the edge of the body-die I, by which a blank will be severed from the rod and crowded into the body-dies, they acting by pressure on the opposite sides of the blank. A retroactive spring, P, is applied to each set of toggles, as seen in Fig. 1, for the purpose of moving them back and opening the dies after each type has been made.

Each feeding apparatus is composed of a lever, R, a nipper, S, and a rod, T, provided with shoulders U V, arranged as seen in the drawings. The lever R turns on a pin or fulcrum, W, and is connected to the adjacent set of toggles, G G or E E, by an extension of their pitman, which slides freely through the frame A, and is jointed to the lever at one end of it.

The nipper, formed as shown in Figs. 1 and 3, is carried in the end of the lever R, which is bifurcated for the reception of the nipper, such nipper turning on a pin, d, extending down through it and the lever, and sliding on the rod T. During the time that each of the two toggles of each set are being moved toward a straight line with each other the lever R will be moved so as to force the type-rod inward between the dies, it being held to the lever by the nipper, which previously has been forced against it by the action of the outer shoulder, U, of the rod T during the

previous return movement of the lever R. During the forward movement of the lever R the feeding-nipper is carried against the shoulder V and moved out of contact with the type-rod and so as to enable the lever to be moved backward without carrying the type-rod with it. By my arrangement of the mechanism types may be made simultaneously at the two opposite corners of the machine and whenever the cam is in action upon the pitmen D D D D.

I claim—

1. For making type, the above-described combination and arrangement of the stationary

body or bed die I, a bottoming-die, M, and receiving-orifice N.

2. The combination of the feeding-lever R, the nipper S, and the rod T, provided with shoulders U V, as set forth, the whole being for the purpose of feeding the type-rod into the mechanism or its dies, as specified.

In testimony whereof I have hereunto set my signature this 21st day of July, 1855.

SAMUEL S. WEED.
